ARRANGEMENT FOR PRODUCING RECTANGULAR ALTERNATING CURRENTS

Dietrich Prinz, Berlin, Germany, assignor to
 Telefunken Gesellschaft für Drahtlose Tele-
 graphie m. b. H., Berlin, Germany, a corpora-
 tion of Germany

Application February 17, 1933, Serial No. 657,247
 In Germany February 19, 1932

11 Claims. (Cl. 250—36)

An object of the present invention is to generate alternating voltages and currents, the curves of which have a rectangular shape.

The invention, which utilizes systems having irregular current voltage characteristic, i. e., in which a continuous variation of the applied voltage, or the current passing therethrough, causes a sudden change of the current passed through the system, or the applied voltage respectively, will now be described. In describing the invention reference will be made to the attached drawing, in which:

Figures 1 and 2, serve to illustrate the principle of the invention;

Figure 3 shows a circuit arranged in accordance with the invention; and

Figure 4 schematically represents the time of pulsations of the individual glow discharge systems of Figure 3.

In the following description these systems are simply designated as "relaxation systems" and as such they are known in great numbers. Any system having a falling characteristic may become a relaxation system by suitably connecting it, in a known manner, with ohmic resistances, such as, for instance, gas filled discharge tubes (glow tube), dynatron, magnetron, Habann-tube, high vacuum tube circuits with ohmic back coupling, etc. The high vacuum tube circuits are better suited due to their small inertia, particularly when used for high frequencies. However, for the sake of simplicity in the following examples the relaxation system is represented by the glow tube.

A relaxation circuit may be characterized by the fact that it may assume two different states for the same outer condition either one of which depends only upon the preceding condition. Thus, for instance, a glow tube with a potential applied to it, whose value is between its ignition potential and its extinction potential, may either be permeable or impermeable to the current, depending upon whether the potential applied previously was higher than the ignition potential or lower than the extinction potential. An increase beyond the ignition potential, or a decrease below the extinction potential, respectively, during practically any short period, is sufficient in order to cause the glow tube to skip over from one state into the other state. This sudden transition may be effected by a current impulse, for instance, which may be impressed upon the relaxation system in any suitable manner. According to Figure 1, the voltage V of the source of current I has a value between the ignition potential and the ex-

tinction potential of the glow tube 2. Connected in series therewith is a resistance 3 having a value R through which a current I , supplied by another voltage source, not shown, may be passed. Hence, the voltage drop RI is added to or subtracted from the voltage V in accordance with the direction of the current I . If $V+RI$ is greater than the ignition potential and if $V-RI$ is lower than the extinction potential of the glow tube, then the latter may be ignited by a current impulse of any short period, in one direction, which has the value I and it may be extinguished by a current impulse in the opposite direction.

Furthermore, it is known to cause such relaxation circuits to produce oscillations, so-called relaxation oscillations, by connecting them in circuit with ohmic resistances and capacities or inductances. Such a circuit is shown in Figure 2, wherein numeral 1 designates a direct current source, 2 is a glow tube, or any other device with a characteristic exhibiting discontinuity, 3 represents an ohmic resistance, and 4 is a condenser. The latter is charged gradually by the voltage I across the resistance 3 until the ignition potential of the glow tube 2 is attained, whereafter it discharges through the glow tube until the extinction potential is reached and then it is charged again, etc. During every discharge a short current impulse passes through the glow tube.

Now, according to the present invention, in order to produce rectangular alternating current curves, two "oscillating" relaxation circuits, as per Figure 2, are combined with the unstable relaxation circuit shown in Figure 1, in such a manner that a current shock of one oscillating circuit causes the unstable system to alternately skip over from its original state into the other possible state, while a current shock of the other oscillating circuit causes the unstable system to drop back into the original state.

Figure 3 discloses an embodiment of the invention shown by way of example.

The section ab of the common source 5 influences the oscillating system I (6 7 8 9) and the section cd acts upon the oscillating system II (10 11 12 13). Therefore the glow tubes 9 and 13 glow periodically, so that periodic currents of short duration pass through the coupling resistances 8 and 12.

The voltage drop of the section bd of the current source 5 has a value between the ignition and the extinction potential of the glow tube 14. By a suitable design of the resistances 8 and 12, the currents passing through these resistances 85

during the glow period of the tubes 9 and 13 cause the glow tube 14 to glow or to be extinguished in accordance with the manner above described.

If now at the time t_1 the glow tube 9 glows and likewise the glow tube 13 at the time t_2 and the glow tube 9 again at the time t'_1 , then the glow tube 14 will be illuminated during the time t_1 to t_2 which means that it is being passed by the current and that between t_2 and t_1 it will be dark, therefore no current flows during this time. It will thus be seen that the current passed through the glow tube 14 has the desired rectangularly shaped curve.

In order to secure a periodically repeated operation, the two oscillating relaxation circuits must have an exactly identical frequency. This may be accomplished, as shown in Figure 3, by means of the alternating current transformer 17 coupling resistance 18 and condenser 19 and/or auxiliary electrodes 15 and 16 causing an alternating voltage having a curve of any shape and having a constant frequency, to act upon the glow discharge tubes 9 and 13 in the oscillating relaxation system. The frequency of the auxiliary voltage may hereby be a multiple of even number of the required relaxation frequency.

In using glow tubes it is sufficient to apply the alternating voltage to an outer metal layer, as shown at 15 and 16 of Figure 3.

The length of the single rectangular oscillations, i. e. the duration of the current flow through the unstable system, glow tube 14, may be regulated in a simple manner by a corresponding variation of the phase with which the alternating voltage acts upon the two oscillating circuits, since, by these phases, the periods t_1 and t_2 are determined, during which the current appears in the circuit I and II, respectively, and therefore the sudden transition and the dropping back of the unstable system takes place. The difference in phase determines the time $t_2 - t_1$ during which the unstable system is caused to assume one of the two possible states (current flow through glow tube 14). In Figure 4 these operations are schematically represented.

In the arrangement of Figure 3 the regulation of the phase is indicated by the provision of a connection of the alternating current source 17 with the auxiliary electrode 15 across an ohmic resistance 18 and with the auxiliary electrode 16 across a variable condenser 19.

Having thus described my invention and the operation thereof, what I claim is:

1. An oscillation generator circuit comprising three glow discharge devices serially connected together, means for producing an intermittent discharge in one of the outer located glow discharge devices, and means for producing an intermittent discharge in the other outer located glow discharge device whose time of occurrence lies between that of the discharges of said first outer located device, means in circuit with one of said two outer devices for causing said third glow device to strike, and in circuit with the other of said outer devices for causing the cessation of the glow in said third device.

2. An oscillation generator circuit comprising three glow discharge devices connected in series, individual condensers connected in parallel across the two outer glow devices, a circuit including a source of unidirectional potential for charging said condensers and causing same to discharge across said devices to produce intermittent discharges the frequency of which is determined in

part at least by the rate of charge of the condensers which on reaching a certain voltage limit discharge themselves through their associated glow devices, means for causing the time of occurrence of the discharges of the two condensers through their respective devices to be different and said third glow device to be responsive to the functioning of both of said outer glow devices.

3. An oscillation generator circuit comprising three glow discharge devices connected in series, individual condensers connected in parallel across the two outer glow devices, a circuit including a source of unidirectional potential for charging said condensers and causing same to discharge across said devices to produce intermittent discharges the frequency of which is determined in part at least by the rate of charge of the condensers which on reaching a certain voltage limit discharge themselves through their associated glow devices, means for causing the time of occurrence of the discharges of the two condensers through their respective devices to be different and said third glow device to be responsive to the functioning of both of said outer glow devices, and a source of oscillations in circuit with both of said outer glow devices for stabilizing the frequency of the intermittent discharges produced.

4. An oscillation generator circuit comprising three glow discharge devices connected in series, individual condensers connected in parallel across the two outer glow devices, a circuit including a source of unidirectional potential for charging said condensers and causing same to discharge across said devices to produce intermittent discharges the frequency of which is determined in part at least by the rate of charge of the condensers which on reaching a certain voltage limit discharge themselves through their associated glow devices, means for causing the time of occurrence of the discharges of the two condensers through their respective devices to be different and said third glow device to be responsive to the functioning of one of said outer glow devices to glow and to the functioning of the other of said outer glow devices to cease glowing.

5. An oscillation generator circuit comprising three glow discharge devices connected in series, individual condensers connected in parallel across the two outer glow devices, a circuit including a source of unidirectional potential for charging said condensers and causing same to discharge across said devices to produce intermittent discharges the frequency of which is determined in part at least by the rate of charge of the condensers which on reaching a certain voltage limit discharge themselves through their associated glow devices, means for causing the time of occurrence of the discharges of the two condensers through their respective devices to be different and said third glow device to be responsive to the functioning of one of said outer glow devices to glow and to the functioning of the other of said outer glow devices to cease glowing, and a source of oscillations in circuit with both of said outer glow devices for stabilizing the frequency of the intermittent discharges produced.

6. An oscillation generator circuit comprising three glow discharge devices connected in series, each of said devices being constituted by two electrodes within a single container, individual condensers connected in parallel across the two outer glow devices, a circuit including a source of unidirectional potential for charging said

condensers and causing same to discharge across said devices to produce intermittent discharges whose times of occurrence across the respective devices are different and the frequency of which is determined in part at least by the rate of charge of the condensers which on reaching a certain voltage limit discharge themselves through their associated glow devices, means for causing said third glow device to be responsive to the functioning of both of said outer glow devices, a source of oscillations for stabilizing the frequency of the intermittent discharges of said outer glow devices, individual auxiliary electrodes for each of said outer glow devices, a condenser connected in series with both of the auxiliary electrodes of both of said outer glow devices, a resistance connected to one plate of said last condenser, said source of oscillations being effectively connected in series with said resistance and last condenser.

7. A system as defined in claim 6, characterized in this, that said auxiliary electrodes are external of their associated glow device envelopes and said last condenser is variable.

8. A square wave oscillation generator circuit comprising three glow discharge devices connected in series, individual condensers connected in parallel across the two outer glow devices, a circuit including a source of unidirectional potential for charging said condensers and causing same to discharge across said devices to produce intermittent discharges whose times of occurrence across the respective devices are different and the frequency of which is determined in part at least by the rate of charge of the condensers which on reaching a certain voltage limit discharge themselves through their associated glow devices, means for causing said third glow de-

vice to be responsive to the initiation of the discharge in one of the outer glow devices to glow and responsive to the commencement of the discharge in the other glow device to cease glowing, the time interval between the occurrence of the discharges of the two outer devices being the duration of the discharge in the third glow device.

9. A relaxation oscillation generator comprising two circuit arrangements both of which generate periodically occurring impulses of the same frequency which do not occur simultaneously, and a third circuit arrangement for generating impulses coupled to said first two circuit arrangements and responsive to one of said two circuit arrangements for initiating an impulse and to the other for stopping said impulse.

10. A relaxation oscillation circuit having, in combination, two generating systems, both of which generate periodically occurring impulses of the same frequency whose times of occurrence are different and a utilization circuit having two conditions of equilibrium coupled to said two systems and responsive to an impulse from one of said systems for effecting one condition of equilibrium and responsive to an impulse from the other of said generating systems for effecting the other condition of equilibrium.

11. The method of generating waves which comprises generating oscillations of one frequency, generating other oscillations of the same frequency, but whose times of occurrence are different from those of the first oscillations and controlling the inception of the generation of still further waves from said first generated oscillations and the completion of said waves from said other generated oscillations.
